DISPLAY RACK

Morris A. Wolf, Dallas, Tex.

Application October 26, 1939, Serial No. 301,481

3 Claims. (Cl. 211—13)

This invention relates to merchandise display racks having particular reference to a rack for the display of men's shirts as disclosed in applicant's Patent No. 2,160,050 issued May 30, 1939.

5 In the former invention covered by the patent referred to above, the principal objects of the invention were to provide a merchandise display rack wherein the merchandise displayed thereon is readily available for inspection, relatively small counter space being necessary for the display, and having a series of independent merchandise display units or frames in the form of hinged wickets whereon the shirt or other article was displayed. The connecting ends of 10 15 15 the wickets were hinged by pins to the base of the structure which was open at the top.

The present invention seeks to improve the display rack by providing a better and more neat appearance of the base structure, by connecting 20 20 25 the wickets to the base in a more suitable manner, and by providing a shell which covers the entire arrangement whereby the wickets are hinged to the base without the pins referred to above. Slight alterations are also 25 made in the wicket structure.

The invention will be better understood by reference to the following detailed description, taken in connection with the accompanying drawing, and in the drawing:

30 Figure 1 is a perspective view of the improved rack illustrating a plurality of men's shirts displayed thereon;

Figure 2 is a perspective view of one of the wickets removed from the rack;

35 Figure 3 is a bottom view of a portion of the base of the rack;

Figure 4 is a cross-sectional view of Figure 3, had on the line 4—4 of said figure, but in a reversed position; and

40 Figure 5 is a fragmentary view in side elevation of part of the base and wickets of the rack.

In carrying the present invention there is provided a base which consists of a shell of metal such as 1, the sides and ends 2 being directed 45 downwardly in such a manner as to provide a relatively flat and forwardly-slanting top wall 3. Strips 4 are placed along the sides of the shell and act as a means of support in connection with the rubber buttons 5 to prevent counter 50 abrasure.

Within the shell thus formed are provided angular strips 6 which may be fastened to a projecting portion 7 of the underside of the top, preferably by welding. These strips extend from 55 end to end of the base or shell and the outer

marginal portions thereof are formed into channels 8. The channel portions are provided with spaced apertures for reception of the ends of the wickets. The wickets, one of which is shown in Figure 2 and indicated by the letter W are so formed that their lower ends at 10 project through the spaced holes referred to, no pins being required, and are thus free to swing forwardly or backwardly as indicated in Figure 5. This forward or backward movement of the wickets is 10 limited by slots S formed in the top 3 of the shell, and through which the legs 9 of the wickets project. The legs 9 are bent over at the upper portions and extend downwardly forming the auxiliary loops 11 and are then bent backwardly as at 12 and then upwardly to provide the main loop 13 (see Figure 2). The loop 13 in the present invention instead of being straight as in the former structure is bent as at 14, providing a curve to more conveniently conform to the 20 collar of the shirts indicated at 15. The shirts as will be obvious, are held in position between the loops 11 and 13 of the wickets W, and may be swung either forwardly or backwardly as indicated in Figure 5 for convenient display, each 25 of the wickets being independent of the other. The improved base, including the shell, provides a covering which presents a neat appearance.

The invention, however, is susceptible to further modifications, such as would be within the meaning of the appended claims.

What is claimed is:

1. A merchandise display rack including a base portion, a plurality of individual units hingedly mounted in said base portion, said base portion comprising a shell or covering with top, side and end walls, and open at the bottom, the top wall including a depression, each of said units adapted to be swung forwardly or rearwardly to display the front and rear portions of merchandise upon said units, and means on said base adapted to co-act with said units for holding the same in spaced apart relation throughout at both limits of their swinging movement whereby 45 merchandise on each unit may be maintained out of contact with merchandise on the adjacent unit in both the forward and rearward positions of the units.

2. A merchandise display rack as set forth in 50 claim 1, wherein the base is provided with parallel spaced angular strips having a channel in each strip and a plurality of spaced apertures within which the legs of the units are mounted, and wherein the top of the shell or base is for- 55

- wardly slanted and provided with a plurality of spaced slots through which the legs of the wickets project, said slots serving to limit the forward and rearward swinging movement of the wickets.
- 5 3. For use with a display rack having a base, a display unit for supporting shirts or the like adapted to be mounted on said base, said unit comprising a wicket including a main loop portion in one vertical plane and a pair of auxiliary side loops formed integral with the main loop and arranged in a plane spaced from but

parallel thereto, the auxiliary loops each including a vertical leg portion adapted to be hingedly secured at its lower end to said base, said main loop including a curved portion to lie adjacent the collar of the shirt, said main and auxiliary loops being of substantially the same height and sufficiently high to support the shirts between them when the wickets are tilted either forwardly or rearwardly of the vertical position. 5
